CLAIM

The ornamental design for a beverage glass, as shown and described.

DESCRIPTION

FIG. 1 is a perspective view of a beverage glass showing my new design;

FIG. 2 is a side view thereof, the opposite side being a mirror image;

FIG. 3 is a front view thereof, the rear view being a mirror image;

FIG. 4 is a top view thereof; and,

FIG. 5 is a bottom view thereof.

The portions of the beverage glass shown in broken line form no part of the claimed design.

1 Claim, 5 Drawing Sheets
